UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP STOP-MOTION.

1,375,743.

Specification of Letters Patent. Patented Apr. 26, 1921.

Application filed February 19, 1920. Serial No. 359,834.

To all whom it may concern:

Be it known that I, RICHARD GREENLEAF TURNER, a citizen of the United States, residing at Worcester, in the county of 5 Worcester and State of Massachusetts, have invented a new and useful Warp Stop-Motion, of which the following is a specification.

This invention relates to a warp stop motion for looms of the type in which a single drop wire is used to indicate breakage of either one of two adjacent warp threads.

It is the object of my invention to provide a warp stop motion in which angular 15 movement of a drop wire from normal vertical position will effect loom stoppage. Breakage of one of the two supporting warp threads will cause displacement of the drop wire in one direction, while breakage of 20 the other supporting warp thread will cause similar displacement in the opposite direction.

In the drawings, I have shown my invention as embodied in a warp stop motion 25 of the general type shown in the Regan Patent No. 1,265,112, issued May 7, 1918, in which indicating bars extend through openings in the drop wires, and in which the loom is stopped when free angular movement of the indicating bars is prevented.

Further features of my invention relate to arrangements and combinations of parts which will be hereinafter described, and more particularly pointed out in the appended claims.

Two forms of my invention are shown in the drawings, in which—

Figure 1 shows my improved construction in front elevation and the drop wires 40 omitted;

Fig. 2 shows the same parts in side elevation;

Figs. 3 and 4 are diagrammatic side elevations illustrating the operation of the 45 device;

Figs. 5 and 6 represent the drop wire in inoperative and operative positions, and

Fig. 7 shows a modified form of drop wire.

Referring to the drawings my improved 50 stop motion comprises a frame 10 supported on rods 11, which in turn are supported by the loom side. A cross rod 12 preferably of triangular cross section connects the two opposite side members of the

frame 10, and an indicating bar 13 is mounted in bearing blocks 14 rotatable in the frame 10. A depending arm 15 is secured to the bar 13 or to the block 14 and is provided with a stud or projection 16 extending into a slot 17 formed in the lower end of an actuator 18.

The actuator 18 is pivoted on a stud 19 fixed in the lower end of an arm 20 forming part of a member 21 pivoted on a stud 65 22 projecting from the frame 10. The member 21 is regularly oscillated by a link 23 by which it is connected to suitable driving mechanism (not shown).

A slide 24 is mounted on the side of the 70 member 21 in alignment with the stud 19 and is yieldingly pressed against a flat surface on the side of the actuator 18 by a spring 25 (Fig. 2). The slide and spring thus maintain the actuator 18 yieldingly in 75 normal position with a stud 26 in an upwardly projecting arm 27 of the actuator aligned with the stud 22 on the frame 10.

The stud 26 furnishes a bearing for one end of the connector 28 through which the 80 loom stopping mechanism is controlled, said mechanism being rendered operative by movement of the connector 28 in either direction. One example of such loom stopping mechanism is found in the patent to 85 Richardson, No. 1,268,152, issued June 4, 1918.

The drop wires W used in my improved stop motion are preferably of the form shown in Figs. 5 and 6, each wire comprising a flat body portion having a long substantially T-shaped opening in the center thereof. The lateral portions 30 at the upper end of the opening are contracted to engage the indicator bar 13 and prevent 90 angular movement thereof. An enlarged opening 31 is provided at the point where the vertical portion 32 and the lateral portions 30 of the slot are joined, in which enlarged opening free angular movement of 95 the indicator bar is permitted. The rod 12 extends through an enlarged intermediate portion 33 of the vertical slot 32 and acts as a guide for the drop wires and also as a support for the warp threads.

Each drop wire W is also preferably provided with spaced projections 34 adapted to engage adjacent warp threads T and T', which support the drop wires W by such engagement. A wire thus supported is 110

shown in Fig. 5 and the angular displacement which follows the breaking of one of the two warp threads is clearly shown in Fig. 6. It will be seen that a drop wire 5 after warp breakage moves angularly until the indicator bar 13 is received in one of the two contracted lateral end portions 30 of the opening in the wire.

The subsequent operation of the device 10 will be better understood by reference to Figs. 3 and 4. So long as the indicating bar 13 is free to move angularly (Fig. 3), the actuator 18 turns with the member 21 about the axis of the stud 22 and in so 15 doing rocks the arm 15 and gives the indicator bar 13 an angular movement. When, however, such movement of the bar is prevented by engagement thereof by a fallen drop wire (Fig. 6), the stud 16 (Fig. 4) 20 becomes the center of movement for the actuator 18 and continued movement of the member 21 moves the stud 26 in the arm 27 of the actuator to the dotted line position in Fig. 4, thus causing longitudinal 25 movement of the connector 28 which in turn stops the loom. If the warp thread T' instead of the thread T were broken, the operation would be the same, but the drop wire W would be tilted in the opposite direction and the displacement of the connector 28 would also occur in the opposite 30 direction.

If both warp threads supporting a single drop wire are broken at the same time, the 35 wire may fall directly downward instead of moving angularly. The wire may then be supported in mid-position for a short time but the convex upper edge of the transverse slot facilitates movement of the wire in one 40 direction or the other so that it is soon tilted sufficiently to engage the bar 13 and stop the loom.

In Fig. 7 I have shown a modified form 45 of drop wire W' in which the central vertical slot is omitted, and in which the supporting rod 12 is replaced by a pair of rods 35 extending along the sides of the drop wires. The action of the wire will be the same as previously set forth.

Having thus described my invention, it 50 will be seen that I have utilized the principle of the Regan stop-motion, while at the same time reducing by one-half a number of drop wires necessary for its operation. This result is of particular importance in silk looms 55 in which a very large number of fine warp threads are used.

It will be evident that other changes and 60 modifications may be made in my invention by those skilled in the art within the spirit and scope thereof as set forth in the claims, and I do not wish to be otherwise limited to the details herein disclosed, but what I do claim is—

1. In a loom, a warp stop motion compris-

ing a plurality of drop wires each sustained in inoperative position by the joint action of two adjacent warp threads, an indicating bar extending through said drop wires, means to give said bar an oscillating angular indicating movement, such movement being prevented by a fallen drop wire on the breaking of either warp thread sustaining said wire although the other thread sustaining said wire remains unbroken, a loom 70 stopping connection, and means to render said connection operative when angular movement of said bar is thus prevented.

2. In a loom, a warp stop-motion comprising a plurality of drop wires supported for 80 substantial angular movement, an indicating bar extending through said drop wires and having a free angular indicating movement when said drop wires are in mid-position but held from such movement when 85 said drop wires are substantially displaced angularly in either direction, means to move said indicating bar, a connection effective to cause stoppage of the loom when displaced longitudinally in either direction, 90 and means to effect such displacement when free angular indicating movement of the said bar is prevented.

3. In a loom, a warp stop motion comprising a plurality of drop wires sustained in inoperative position by the joint action of two adjacent warp threads, an indicating bar extending through said drop wires, means to give said bar an oscillating angular indicating movement, and loom stopping mechanism controlled by said indicating bar, any one of said drop wires upon the breakage of either of its sustaining threads becoming effective to prevent further angular indicating movement of said bar and to thereby 100 stop the loom, although the other thread sustaining said wire remains unbroken.

4. In a loom, a drop wire comprising a body having a laterally extending opening in its upper portion, enlarged at the center and reduced at both ends, and having also two laterally separated warp thread receiving openings, said wire being normally supported by warp threads extending through said openings.

5. In a loom, a drop wire comprising a body having a laterally extending opening in its upper end enlarged at the center and reduced at both ends, and having warp thread engaging projections on each side of said body, whereby said wire is normally supported on two adjacent warp threads.

6. In a loom, a drop wire comprising a body having a substantially T-shaped slot therein, reduced at its extreme lateral portions, and having two thread receiving openings one on each side of said central slot but spaced therefrom.

7. In a warp stop-motion, a drop wire having a body with a long central substan-

tially T-shaped slot open at its lower end, and having two separated thread engaging portions.

8. In a loom, a drop wire comprising a body having a substantially T-shaped slot therein, reduced at its extreme lateral portions and having an enlargement intermediate the upper and lower ends of said slot, said drop wire having also separated warp 15 thread engaging projections, one on each side of said slot.

9. In a loom, a drop wire comprising a body having a laterally extending opening in its upper portion, and having also two laterally separated warp thread receiving 15 openings, said laterally extending opening being enlarged at the center and reduced at both ends and having its upper edge convex downwardly.

In testimony whereof I have hereunto 20 affixed my signature.

RICHARD GREENLEAF TURNER.
